UNITED STATES PATENT OFFICE.

ROBERT J. EMORY, OF NEWARK, NEW JERSEY.

REAMER.

1,378,339.

Specification of Letters Patent. Patented May 17, 1921.

Application filed April 15, 1919. Serial No. 290,205.

To all whom it may concern:

Be it known that I, ROBERT J. EMORY, a citizen of the United States, and resident of Newark, in the county of Essex and State 5 of New Jersey, have invented certain new and useful Improvements in Reamers, of which the following is a specification.

The invention relates to an adjustable reamer of the type of such tools in which 10 the diameter can be varied at will so as to ream different size holes within the capacity of the tool.

In known devices of this type the elements which go to make up the cutting 15 edges have been adjustable in the body portion of the tool by various means but these attempts to provide for adjustment have not proved satisfactory and in the case of small size reamers of this type it is physically impossible to provide for both sensitivity 20 adjustment and for the desired rigidity of the cutting members.

Accordingly one of the objects of the invention is to provide a simple form of 25 reamer which will be characterized by rigidity of cutting edges and incidental freedom from chattering and at the same time possess means providing microscopic adjustment to fit the variable size openings to be reamed.

Broadly, this object is attained by forming 30 the cutting edges in the body portion of the tool so as to maintain the rigidity of parts present in the fixed-diametered reamers and to provide a bearing member adjustable 35 radially relative to the axis of rotation of the tool thereby to vary the maximum diameter of the tool.

The invention further features a simple 40 form of construction which can be manufactured cheaply compared with devices of this general type and incidental to this desideratum another object of the invention is to provide a device of the class described which can be machined with relatively 45 small changes in present manufacturing methods and in which the relatively movable parts are designed to minimize wear and can be readily replaced if necessary.

Various other objects and advantages of 50 the invention will be in part obvious from an inspection of the accompanying drawings and in part will be more fully set forth in the following particular description of one form of mechanism embodying my invention, and the invention also consists in certain new and novel features of construc-

tion and combination of parts hereinafter set forth and claimed.

Referring to the accompanying drawings:—

Figure 1 is a view in side elevation of a preferred embodiment of the invention;

Fig. 2 is a similar view partially in axial section;

Fig. 3 is a transverse sectional view taken 65 on the line 3—3 of Fig. 2; and

Fig. 4 is an end view of the reamer shown in the preceding figures with the guide strip extended and engaging in the hole to be reamed.

In the following description and in the claims, parts will be identified by specific names for convenience of expression but they are intended to be as generic in their application to similar parts as the art will 70 permit.

A reamer 10 of the fluted cylindrical type has been selected to show the invention but it is obvious that the invention is applicable to other forms of reamers and with obvious 80 mechanical changes is applied to other similar forms of cutting tools, such as taps and broaches, designed to fit in holes to be machined.

The reamer includes the usual shaft or 85 body 11, in the side of which are formed, as by fluting, one or more cutting edges 12 fashioned in any manner usual with the conventional form of fixed-diametered reamers.

The device differs from the conventional 90 form in having the unfluted side of the reamer smooth to form a back bearing surface 12.

As thus far described the tool functions as does the conventional reamer for in both 95 cases the cutting edges are formed in the massive body portion of the tool.

The surface 12 is provided with a longitudinally extending slot 13 in which is fitted a long bearing strip 14 of a length at least 100 coextensive with the cutting part of the tool.

This strip is held in place by bands 15 in the form of split rings which fit in circumferential grooves 16, formed in the body 11 and in the strip adjacent opposite ends 17. 105 This construction permits freedom of movement of the strip radially of the tool but defeats any tendency of the strip to move longitudinally. The body portion is provided opposite the center of the strip with 110 a threaded aperture 18 which extends from the bottom one of the grooves 19 forming

the cutting edges 12 to the bottom of the slot 13. A small headed set screw 20 into the aperture 18 is positioned to move into bearing engagement with the strip 14 to move the same radially and thus move the outer, hole-engaging surface 21 of the strip from its normal position flush with the surface 12 into any desired position spaced from the surface 12.

10 In operation and assuming that it is desired to ream a hole to a diameter greater than the diameter which the tool would cut when the strip 14 is fully seated in its guiding slot, the screw 20 is adjusted until the measured diameter between the surface 21 and the diametrically opposite cutting edge 12 calipers to the desired measurement. Due to its rigidity and to the fact that the spring bands apply equal pressure at points 15 on both sides of the screw 21 equally spaced therefrom, the strip will move parallel or substantially parallel to the axis of the tool springing the holding rings at opposite ends. Releasing the pressure of the set screw will permit the rings to react on the strip and move the same toward its seated position in the slot.

10 In the alternate it may be desired in some forms of work to set the strip at variable angles to the axis of the tool. In this case the tool can be provided with two apertures 30 21 and 22 similar to the aperture 18 and positioned adjacent opposite ends of the strip. Screws similar to the screw 20 may be inserted in these end apertures and by suitably adjusting the screws any desired angularity of the strip within the capacity of the tool may be attained. In this operation, when a screw is turned to move one end of 35 the strip outwardly, the spring band distant from said screw will cause the distant end of the strip to fulcrum.

10 While the preferred form features the bearing strip as having a smooth hole engaging face, it is an obvious modification 45 to utilize this strip as an additional cutting member and this may be desirable in situations where a continuous series of cutting edges about the entire surface of the tool 50 is desired.

By means of a device of this character

any desired size hole may be reamed accurately, for any variation due to the regrinding of the cutting edges can be compensated for by the adjustment of the bearing strip. The tool does not chatter but quietly reams the hole to the desired diameter.

While I have shown and described, and have pointed out in the annexed claims, certain novel features of my invention, it will be understood that various omissions, substitutions and changes in the form and details of the device illustrated and in its operation may be made by those skilled in 65 the art without departing from the spirit of the invention.

Having thus described my invention, I claim:

1. A tool designed to engage in a hole 70 to machine the same, said tool including a shaft provided with a slot extending lengthwise thereof, a bearing strip fitted in said slot, said shaft and strip provided with recesses coacting to form a continuous peripheral groove, a retaining ring fitted in said groove for preventing relative lateral movement between the strip and shaft, and a set screw threaded diametrically through the shaft and engaging the strip to advance the 80 same radially out of the slot.

2. A tool designed to engage in a hole to machine the same, said tool including a shaft provided with a slot extending lengthwise thereof, a bearing strip fitted in said slot, 85 said shaft and strip being provided with recesses coacting to form two continuous peripheral grooves, expansible retaining rings fitted in said grooves for preventing relative lateral movement between the strip and the shaft, said shaft having therethrough three threaded passages intermediate the rings, whereby upon the insertion of a threaded member into one of the 90 passages, the strip can be given either a 95 bodily parallel movement, or an angular movement.

Signed at New York city in the county of New York and State of New York this 8th day of April, A. D. 1919.

ROBERT J. EMORY.
